DOUBLE CONTAINER

Martin E. Mayer, New York, N. Y., assignor to
Joseph Solomon, New York, N. Y.

Application August 25, 1950, Serial No. 181,552

9 Claims. (Cl. 215—6)

1

This invention relates to receptacle structures and more particularly to jars and similar containers made of glass, plastic or plastic composition or like transparent mass.

In its broad aspects the invention deals with a dual or partitioned container for holding substances of different consistencies and color contrasts, which substances may be dispensed from opposite openings of said container, respectively. The invention is applicable to cylindrical, as well as to other suitably shaped containers, which may be of convex or bulbous body configuration and are provided with opposite opening ends, which are closable by caps, such as screw caps of conventional design.

It is a well known fact that containers of the aforesaid type require a predetermined volume of air or a so-called "head space" which extends between the surface of the liquid or other substance filled in and occupying the interior of the container and the inner surface of the screw cap or like closure seated on the rim of the opening of the container.

If such container filled with said substance is turned upside down, the aforesaid "head space" will become noticeable at the bottom of the container.

If the container is constructed to contain a plurality of substances which are separated from each other by a partition which runs across the middle of the container and forms the bottom, say, of a dual container, then the "head space" in each opposite container portion will become visible adjacent said partition, whenever the container is placed to rest on one or the other of the closure or screw cap of the container.

The appearance and demarkation of such "head space" in a dual or divided container having several compartments entails, however, disadvantages which offset utility and usefulness of such containers.

The invention does away with these and other objections and proposes means affording the employment of horizontally divided or partitioned containers having several compartments and considerably enhancing display, promotion and salability of products having color contrast with respect to each other.

Another object of the present invention is to provide means facilitating accommodation of a portion of the substance which is contained in either of the container compartments, in a respective recess or recesses of the partition, which portion corresponds to the aforesaid volume of air or "head space" required in the respective compartment.

2

A further object of the invention is to provide means rendering possible simplification and effectiveness of dual or partitioned containers of the aforesaid type, which permit dispensing of at least two different substances, such as liquids, from within a transparent shell or housing which defines the outer surface of the dual container.

Yet another object of the invention is the provision of means conducive to an economical and space saving container structure, which requires a reduced quantity of packaging operation and material as compared with packaging of regular containers holding like volumes.

With the above and other objects in view, the invention will be hereinafter more fully described and the combination and arrangement of parts will be shown in the accompanying drawing and pointed out in the claims which form part of the specification.

In the drawing:

Fig. 1 is a vertical cross sectional view through a container showing the state of the art.

Fig. 2 is a vertical sectional view of a container made in accordance with the invention.

Fig. 3 shows a container partly in section embodying another form of the invention.

Fig. 4 is a cross sectional view taken along line 4—4 of Fig. 3.

Fig. 5 is a vertical sectional view through a container of a different shape than those seen in Figs. 2 and 3 and embodying the invention in a further modified form.

Referring now more particularly to the drawing and in particular to Fig. 1 there is shown a container 10 forming a jar made of glass and cylindrical in shape. This jar is shown to have two open ends 11 and 12 which are closed by screw caps 13 and 14, respectively. A partition 15 divides container 10 into compartments 15a and 15b, respectively. Compartment 15a is filled with a substance 16 whereas compartment 15b is filled with a substance 17. Substances 16 and 17 are preferably liquids different in color and, if desired, of different consistencies.

It is well known that such containers must have an air or head space 18 which extends between the surface 19 of the substance 16 and the inner surface 20 of cap 13. The same head space 18a is produced in the lower compartment 15b but appears in the latter adjacent partition 15. It is well understood that head space 18 is not visible since it is covered up by container cap 13, whereas head space 18a becomes visible adjacent partition 15, as seen in Fig. 1.

A container constructed as seen in Fig. 1 would

give the impression as if the same was only partly filled with the substance 17, if the container 10 is arranged in upright position, as seen in Fig. 1. If the container is turned for support on cap 13 head space 18 now appearing uppermost and covered by cap 13 would become apparent adjacent partition 15 in a way similar to that of head space 18a.

In order to increase the sale and commercial possibilities of dual jars or containers of the aforesaid type the invention proposes in contradistinction to the construction seen in Fig. 1 to provide a container 30 made from glass or similar transparent material which is cylindrical in cross section and provided at its opposite open ends 31 and 32 with screw threads or similar retaining means 33 and 34 for the engagement of a metal or screw cap 35, 36, respectively. In the present instance screw caps 35 and 36 are provided with an inner layer of cork or similar material 35a, 36a to tightly close the ends of the container 30.

As can be further seen from Fig. 2 container 30 is divided by a suitably shaped partition 37 which has oppositely directed recesses 37a, 37b for a purpose about to be described. As can be seen in Fig. 2 the substance 38a contained in upper compartment 38 forms a head space 39 which is ordinarily not visible to the eye of a person due to the fact that cap 35 covers up and obstructs said head space from view.

However, according to the invention a predetermined volume of substance 38a corresponding to that of the head space 39 is received in recess 37b and is indicated by numeral 39a. The container compartment 40 containing the substance 40a has a head space which corresponds in volume to the volume of air 39b contained in recess 37a whereby since the partition 37 is made of transparent material this air space 39b is shifted and transferred to the middle of the container 30 as compared with the head space 18a seen in Fig. 1.

Consequently head space 39b or the volume of air corresponding to the latter is surrounded by the substances 38a and 40a and will not become exposed to view to the purchaser of such dual container. Thus, it can be readily understood that container 30 may be placed on either cap 35 or 36 without making visible the head space as it would appear in dual containers of conventional design as exemplified in Fig. 1.

Fig. 3 shows a container 50 also circular in shape and made from transparent glass material having the open ends 51 and 52 and the screw threads 53 and 54 for the screw caps 55 and 56. The screw cap 55 has the inner lining 55a whereas screw cap 56 has the inner lining 56a.

The partition 57 which is pressed or in any other way produced together with the outer cylindrical surface 58 of dual container 50 has a plurality of concentrical grooves or recesses of different sizes with a center groove 59 of larger dimension than the adjacent grooves 60, 61.

It is to be noted that straight partition ends or portions 62 and 63 extend in horizontal direction from each end of the grooved transverse partition 57. In this particular execution of the invention the volume of head space 65 of upper compartment 64 corresponds to the volume of substance 66 contained in grooves 57a and 57b. It will be observed that lower compartment 64a having the head space 68 is filled with a substance 69 which has preferably a different color than that of substance 66 of compartment 64,

for instance, marmalade in 64 and blackberry jelly in 64a.

The head space 68 in the lower compartment 64a is hidden from view through the concentrical grooves 57a, 57b, etc., forming parts of partition 57, which grooves are arranged at levels different from the level of portions 62, 63 and remote from the latter, it will be readily understood that said head space 68 of lower compartment 64a will not be exposed to view in a manner as seen, for instance, in Fig. 1. Thus, it will be clear that the partition ends 62, 63 will only divide the container 50 into two equal container halves.

Fig. 5 shows the application of the invention on a bulbous jar 70 having the upper open end 71 and the lower open end 72 which are again closed by suitable screw caps 75 and 76 which engage the screw threads 73 and 74 of the convexly shaped container wall 70a.

Screw cap 75 contains the liner 75a whereas screw cap 76 is associated with liner 76a to tightly fit on the upper rim defining opening 71 and lower rim defining the opening 72, respectively. A partition integral with the wall 70a of the container 70 extends substantially across the container and has the straight partition portions 78, 79 and the upwardly extending receding portions 80 forming an annular space 81 between which extends the downwardly directed central partition portion 82 providing a recess having a volume 83. Thus partition 77 is somewhat shaped in the form of a sinusoidal wave which is disposed at the middle portion of the jar or container 70.

It will thus become apparent that the head space 85 corresponds in volume approximately to the volume 83 of substance 84 contained in the upper compartment 86, whereas annular space 81 communicates with the lower compartment 86a containing substance 87 and corresponding to the head space present and extending between the inner surface of the cap lining 76a and the surface of the substance 87 when container 70 would be placed in upside down position on cap 75.

The volume 83 of substance 84 is about equivalent to the volume 85 of air present in compartment 86, whereas air volume 81 corresponds to the above explained head space of compartment 86a. Both volumes 83 and 81 may be equal to each other, if desired.

While partition portion 80 forms in this particular instance an annulus and central partition portion 82 a cylindrical recess, it is well understood that the aforesaid partition portions may have any other suitable (round, dome-shaped, etc.) configurations or cross-sections, as long as they are adapted to receive and hold the respective air or head space volume of the upper or lower container compartments of the dual container, substantially in the center part of the latter. Such space should not be recognized or perceived by the purchaser, in order not to disturb the aesthetic appearance and feature of sales promotion of the container.

It is to be noted that the contents of the upper and lower container or jar compartments may be equal. It is further to be observed that due to the fact that the recess or recesses communicating with one compartment extend in a direction opposite to that of the recess or recesses communicating with the other of the compartments, the cubical capacity of each compartment is principally not changed with re-

spect to a container having a straight partition, as seen in Fig. 1.

It can thus be seen that there has been provided in accordance with the present invention the provision of a partition in a transparent container having opposite discharge ends, which partition extends substantially in the middle and across the interior of said container, with at least one recess provided in said partition at about the center thereof and in communication with a respective discharge end of said container, the volumetric contents of said one recess corresponding approximately to the volume of air present above the surface of the respective substance and the adjacent inner face of the closure member when closing the respective discharge end.

It is preferred that the partition is made of the same transparent mass and is integral with that of the container although in some cases it might be useful to employ a separate partition which is located within the interior of the container and fixed to the inner wall thereof in any appropriate manner.

Although the invention has been described with reference to certain specific embodiments thereof, it is to be distinctly understood that various modifications and adaptations of the arrangements herein disclosed may be made as may readily occur to persons skilled in the art without constituting a departure from the spirit and scope of the invention as defined in the objects and in the appended claims.

Having thus described the invention, what is claimed as new and desired to be secured by Letters Patent, is:

1. A transparent receptacle for a plurality of substances; comprising a partition extending in substantially horizontal direction across the interior of said receptacle dividing said receptacle into two compartments, said partition including at least two recesses, said recesses being directed in opposed relationship to each other and disposed to extend approximately in the center of said partition, a closable discharge end for each compartment at either end of said receptacle, and a closure having an inner top surface and adapted to be applied to each discharge end, the respective recess communicating with the respective discharge end of either of said compartments being approximately of such dimension as to receive a volume of air substantially equal to and present within the space defined by the surface of the respective substance and said inner top surface of the respective closure of the respective compartment in a predetermined position of said receptacle.

2. A transparent receptacle for a plurality of substances; comprising a partition extending in substantially horizontal direction across the interior of said receptacle dividing said receptacle into two compartments, said partition having a plurality of concentric recesses of different diameters, said recesses opening into the respective compartments, a closable discharge end for each compartment at either end of said receptacle, and a closure for each discharge end, whereby the respective recesses communicating with the respective discharge end of either of

said compartments are dimensioned to receive displaced air from the respective compartment in a predetermined position of said receptacle.

3. A transparent receptacle for a plurality of substances; comprising a partition extending in substantially horizontal direction across the interior of said receptacle and dividing said receptacle into two compartments, said partition being provided with an annular recess and a pocket, said annular recess being directed in opposed relation to said pocket, said pocket and said annular recess being disposed to extend approximately in the center of said partition, a closable discharge end for each compartment at either end of said receptacle, and closure means for each discharge end, said annular recess communicating with the discharge end of one compartment, said pocket communicating with the discharge end of the other compartment.

4. The combination, in a transparent container having opposite discharge ends for a plurality of substances and a closure member for each discharge end, of a partition extending substantially in the middle and across the interior of said container, with at least one recess provided in said partition at about the center thereof and in communication with a respective discharge end of said container, said one recess corresponding in size approximately to the head space defined by the surface of the respective substance and the inner top surface of the closure member closing the respective discharge end.

5. The combination according to claim 4, wherein said partition is provided with end portions which extend in horizontal direction and substantially at right angles to and for connection with the wall of said container.

6. The combination according to claim 4, wherein said partition includes horizontally directed outer end portions and is provided with two substantially centrally located recesses which extend in opposite relation to each other above and below said outer end portions of said partition.

7. The combination according to claim 6, wherein one of said recesses forms an annular channel, the other recess being arranged intermediate said annular channel.

8. The combination according to claim 6, wherein said centrally located recesses are concentrically disposed with respect to each other.

9. The combination according to claim 6, wherein the volumetric capacity of one of said recesses is substantially equal to that of said other recess.
